UNITED STATES PATENT OFFICE.

CLAIR J. AMICK, OF CLEVELAND, OHIO, ASSIGNOR TO THE ALUMINUM CASTINGS COMPANY, OF CLEVELAND, OHIO, A CORPORATION OF OHIO.

MOLD.

1,308,156.

Specification of Letters Patent.

Patented July 1, 1919.

Application filed April 2, 1919. Serial No. 286,883.

To all whom it may concern:

Be it known that I, CLAIR J. AMICK, a citizen of the United States, residing at Cleveland, in the county of Cuyahoga and 5 State of Ohio, have invented certain new and useful Improvements in Molds, of which the following is a specification, reference being had therein to the accompanying drawings.

10 This invention relates more especially to an improved form of gate for molds. While the invention, with respect to some of its features at least, is of general application, it has been developed in connection with 15 molds for casting aluminum alloy internal combustion engine pistons and is especially applicable to the casting of cup-shaped and hollow cylindrical articles from metals or metallic alloys having relatively high crystallization shrinkages, such as characterize 20 the aluminum alloys.

One of the objects of the invention is to avoid the formation of blow holes in the casting due to the occlusion of air or other 25 gases.

Another object of the invention is to avoid porosity and cracks in the casting due to crystallization shrinkage.

A further object is to provide a form of 30 gate, which in addition to preventing blow holes in the castings as above stated, will prevent the passage of gases, metallic oxids and other impurities into the casting cavity.

Another object of the invention is the provision of a mold adapted to attain the foregoing objects and at the same time be relatively compact in form and correspondingly limited in weight.

Other objects more or less incidental to 40 those above stated will be apparent from the following description in which I set forth a preferred embodiment of the invention.

In the drawings,

45 Figure 1 is a top plan view of a mold provided with my improved form of gate.

Fig. 2 is an enlarged fragmentary section on the line 2—2, Fig. 1.

50 Fig. 3 is an enlarged vertical section on the line 3—3, Fig. 1.

Fig. 4 is an enlarged fragmentary vertical section on the line 2—2, Fig. 1, with the core parts removed.

55 Fig. 5 is a horizontal section on the line 5—5, Fig. 3.

Fig. 6 is a horizontal section on the line 6—6, Fig. 3.

Fig. 7 is a section on the broken line 7—7, Fig. 3.

Figs. 8 and 9 are fragmentary horizontal 60 sections on the lines 8—8 and 9—9, respectively, Fig. 3.

The construction illustrated in the drawings shows my improvements embodied in a permanent mold designed for the casting of 65 aluminum alloy internal combustion engine pistons of relatively large size. Referring in detail to the construction illustrated, the mold as shown comprises a plurality of parts adapted when assembled to form a mold cavity, 70 A, for the piston casting proper. The mold body includes a base member 1 and two complementary chambered side members 2 and 3 which are movable on the base to and from each other and thus provide for the removal of the castings in the operation of the mold. These three main sections of the mold body are preferably made of cast iron, 75

The base 1 is formed with a central depression having a cylindrical side wall 1^a, 80 and a flat bottom wall 1^b. Each of the side members 2 and 3 comprises an inner side wall 4, end walls 5 and 6, and top and bottom walls 7 and 8, respectively. The outer side of each of the side members is formed 85 by a plate 9 bolted to the casting, thus closing the interior chamber 10 of the member. Handles 11, 11 are secured to the plates 9, 9 so that the side members of the mold can conveniently be moved to and from operating position on the base.

The inner side walls 4 of the complementary members of the mold body mutually engage with each other when said members are moved together as shown in Fig. 1. The 95 wall 4 is formed between its ends with a semi-cylindrical portion 4^a, and the lower parts of the two semi-cylindrical walls 4^a, together with the cylindrical side wall 1^a in the base, form the upper side wall of the 100 casting cavity proper, the bottom of said cavity being formed by the conical bottom wall 1^b of the depression in the base member. Said conical wall is formed with a central depression 1^c which provides for a 105 "work spot" on the head of the piston casting. The bottom wall of this central depression is formed by a plug 1^d which is grooved on its periphery to provide vents for air and other gases.

To secure alinement of the mold members 2 and 3, in relation to each other, the base is formed with a cylindrical shoulder 12, and coöperating cylindrical shoulders 12^a, 5 12^a, are formed in each of the side members 2, 3. These coöperating shoulders 12 and 12^a, are struck from the same axis and thus serve to effect perfect alinement of the side members in relation to each other. To 10 insure the proper angular positioning of the side members on the base 1, the latter is provided with upstanding dowel pins 13 which engage semi-cylindrical recesses 13^a in the side members 2, 3.

15 The mold is provided with a main core 14 which is preferably made of steel and is of the five part form shown in Figs. 18 to 19 of United States Letters Patent No. 1,296,597 to Frederic A. Parkhurst, and is 20 of the same general character as the core shown in the United States Letters Patent to Joseph H. Bamberg No. 1,296,588. For a detailed description of the core parts reference may be had to said Letters Patent.

25 For the purpose of the present application it will suffice to state that the core comprises a central part 14^a, and two pairs of members 14^b, 14^c and 14^d, 14^e, which when assembled are adapted to be supported at their 30 upper ends in the mold body so as to depend within the cavity formed therein and form the inner walls of the casting cavity proper. The main core parts are supported in the mold body by engagement with a pair of liners 15, 15 which are suitably secured to the mold members 2, 3, as by screws 15^a. The lower ends of the liners serve to form the annular top wall of the mold cavity. With the main core parts supported in the 35 liners 15, as shown in Fig. 2, the mold cavity takes substantially a cup shape corresponding to the trunk or skirted piston which it is desired to cast.

40 To insure proper annular positioning of the core 14 in the mold body, the central member 14^a of the core is provided with a key 16 which projects from the core and is received between wear plates 17 secured in slots in the mold members 2, 3 and their liners 15, 15.

45 The core members 14^b and 14^c are shaped to form a recess 14^g to provide for a wrist pin boss on the casting, while the members 14^d and 14^e are shaped to form a recess 14^h, 50 for a similar purpose.

55 The core 14 is provided with vent passages as follows: The middle part 14^a of the core is formed on its opposite flat faces with longitudinal passages 14^k, 14^k each of which 60 extends from the upper end of the core part to a transverse passage 14^m near the lower end of the core part. Then these flat faces of the core part are formed at their lower ends with a series of vent grooves 14^l, 65 extending from the bottom surface of the core

upward to the transverse passage 14^m, and an adequate vent upward through the core is thus provided for air and gases collecting on the bottom surface of the core. Each of the runners 15 is formed with vent grooves 70 15^b, 15^c, 15^d and 15^e on its bottom, inner, outer and top sides, respectively.

75 18, 18 are removable core pins slidably mounted in the mold members 2, 3 with their inner ends projecting into the boss recesses 14^g, 14^h. To facilitate their removal, said pins have their ends slightly tapered where they engage the mold body and project into the mold cavity.

80 In the operation of the mold the various parts are secured in operative position by lock devices 19, 19 each of which comprises a pin 19^a mounted on one of the side members of the mold and a coöperating pivoted hook 19^b on the other side member. When 85 the side members 2, 3 are brought together in proper position on the base 1, the hooks 19^b are forced down over the pins 19^a so that the parts of the mold body are firmly secured together.

90 I turn now to a description of the gate of the mold to which my improvements more particularly relate. The gate which is formed by alining recesses in the adjacent walls 4, 4 of the mold members 2 and 3, and 95 in the base 1, in its entirety comprises a feeder and a supply conduit. The feeder is in the form of an upright cavity 20 adjacent one side of the casting cavity and extending from the bottom of the casting cavity upward to and above the upper end of said cavity, the upper part of the feeder comprising a riser 20^a extending well above the top of the casting cavity. The feeder communicates with the casting cavity through a 100 short passage 21, said passage extending, preferably, continuously from the bottom to the top of the feeder and being relatively narrow in comparison with the greater width of the feeder cavity.

105 The main part of the feeder cavity is formed by recesses in the walls 4, 4 of the mold members, but the lowermost end thereof is formed by a recess 22 in the mold base. The main part of the feeder 20 is formed 110 opposite the casting cavity and the passage 21 leading thereto, with a downwardly and laterally inclined wall 20^b. At its lower end the inclined wall 20^b joins the inclined wall 22^a which leads to the bottom of the casting cavity.

115 The adjacent faces of the mold members 2 and 3 are formed with vent grooves 23 extending from the top of the feeder chamber 20 to the upper surface of the mold.

120 The supply conduit of the gate comprises a downwardly extending inlet section 24, a laterally and upwardly extending liquid seal section 25, and a downwardly and laterally extending discharge section 26 which opens 125 130

into the top of the feeder cavity 20. At 27, where the inlet section 24 joins the liquid seal section 25, the supply conduit is sharply constricted. This constriction of the passage 5 and the abrupt change of direction serve to strongly check the velocity of the entering molten metal. As the entering metal rises in the supply passage to a level above the point 28 of the upper wall of the passage, a 10 liquid seal is formed so that any oxids or other impurities lighter than the metal will float upon the surface of the metal in the inlet section 24 and be prevented from passing through to the feeder and the casting cavity 15 proper. Obviously this liquid seal will tend to prevent the passage of air with the entering metal.

It will be observed that the discharge section 26 of the supply conduit of the gate is 20 formed and arranged to deliver the molten metal into the top of the feeder cavity on lines substantially parallel to the inclined wall 20^b thereof, thus directing the stream of metal smoothly downward over said wall in 25 a manner to avoid agitation and splashing.

It is usually desirable to provide for heating the body of the metal to maintain it at a suitable temperature and I have shown 30 burners 29, 29 mounted on brackets 30, 30, said burners being arranged so that their flames are directed through openings 9^a in the plates 9 to heat the inner walls of the mold members 2 and 3, and especially the 35 parts of the walls 4 in which the gate is formed, this arrangement insuring that the metal in the gate shall remain molten longer than that in the mold proper.

Preferably the walls of the mold, including 40 core parts, which constitute the walls for the mold cavity are suitably coated or treated in well known manner to reduce as much as possible agitation of the molten metal as it flows into contact therewith and to insure proper setting of the metal within 45 the cavity.

In the operation of the mold above described the members 2 and 3 are first moved into operative position on the base 1, then the sections of the main core 14 are inserted, 50 the locking devices 19 are driven home to tightly lock the mold members 2 and 3 together and firmly clamp the main core in position. Finally the core pins 18 are introduced.

55 The temperatures at which the various parts are maintained will depend largely upon the nature of the metal or alloy to be cast. Assuming that the burners 29 have been operated to heat the mold parts to the 60 desired temperature the mold is now ready to receive the molten metal. Said metal is brought to the mold in any suitable manner, as by ladle, and is poured into the inlet 24 of the gate. The sharp constriction of the gate 65 passage at 27 strongly retards the velocity of

the entering metal as does also the lateral and upward direction of the liquid seal section 25 of the passage into which the metal passes from the inlet section. On account of this marked retarding of the flow the liquid seal 70 section 25 of the gate passage quickly fills and the metal backs up more or less in the inlet section 24, thus forming an effective liquid seal at the point 28, which tends to prevent the entrance of air along with the 75 metal and also insures that any oxids or other impurities lighter than the metal will float up on the surface of the metal in the inlet section 24 of the gate. As the metal backs up in the inlet section 24, it also passes 80 over into the discharge section 26 of the gate conduit and in this section the metal is directed downwardly and laterally along lines substantially parallel to the inclined wall 20^b of the feeder. Thus the molten metal 85 delivered into the top of the feeder is directed smoothly downward at a moderate velocity over the said inclined wall and thence downward to the bottom of the feeder and into the bottom of the casting cavity without 90 agitation and splashing. As the first entering metal flows into the bottom of the casting cavity it spreads out freely and smoothly and there is an entire absence of any localized impact of the entering stream 95 of metal either against the outer walls of the casting cavity or against the core parts.

As the molten metal continues to flow into the mold and its upper surface, in the casting cavity, comes into contact with the lower 100 end of the core 14, the air above the metal either finds its way radially outward and into the annular part of the cavity in which it is free to rise and escape through vent 105 grooves 15^b, 15^c, 15^d and 15^e formed in the 105 liners 15, or, entering the vent grooves 14^a, finds its way upward through the core to the exterior of the mold.

While the venting of air or gases overlying the relatively quiescent mass of rising 110 metal is readily effected in the manner just described, it is to be observed that if there were splashing or agitation of the metal in the mold, air or gas would be occluded in it and it would be practically impossible to 115 separate such air or gas, no matter how adequate the provision for venting might be, and such occlusion of air or gas would, of course, result in serious porosity of the casting. This has been found to be especially 120 true in the case of castings having heavy cross sections.

As the molten metal rises in the feeder and casting cavities, it continues to flow from the feeder cavity through the short 125 narrow passage 21 into the annular section of the casting cavity passing around the main core in both directions, as will readily be understood. During this part of the pouring the entering metal continues to be 130

directed smoothly downward over the inclined wall 20^b of the feeder and thence smoothly into the molten bath accumulated in the lower part of the feeder, and in turn 5 there is a smooth flow of the metal from the feeder through the passage 21 into the casting cavity and, as at the beginning of the pouring, the metal enters the casting cavity with an entire absence of high velocity jet 10 action with resulting impact against the core, splashing and occlusion of air or gas.

When the casting cavity is entirely filled the level of the molten metal continues to rise in the upper part of the feeder cavity 15 until the latter and the supply conduit of the gate are entirely filled, whereupon the pouring ceases.

In the filling of a mold cavity in the shape 20 of a hollow cylinder or of the cup-shaped mold cavity such as that of the present mold, the molten metal gives up its heat to the walls of the mold and tends to freeze first at points remote from the gate or source 25 of supply and then gradually and progressively from said remote points around the main core of the gate. In my improved mold as the metal freezes in the casting cavity proper, compensation for the crystallization shrinkage is afforded by the molten 30 metal which is maintained in the feeder cavity and flows freely at any level through the passage 21 into the casting cavity. In a word, an adequate supply of molten metal is maintained in position to enter the casting 35 cavity at any level to compensate for crystallization shrinkage and a progressive setting of the metal in the mold is secured from points opposite the gate around the main core in both directions, then in the 40 short passage 21 between the casting cavity and the feeder and finally in the feeder itself.

After a short interval to permit the metal 45 to set, the locking devices 19 are eased off, the core parts are withdrawn, the pins 18 somewhat in advance of the main core parts, then the locking devices 19 are entirely disengaged and the mold members 2 and 3 separated to permit removal of the casting.

50 The avoidance, by means of my improved gate, of any high velocity jet action of the molten metal as it enters the casting cavity has been explained but it may be added that the importance of this lies not only in the 55 fact that it obviates splashing of the metal due to sharp impact on the mold walls, but also in the avoidance of a localized heating and wear of the mold walls which would result at the points sustaining the impact 60 of the jet. It has been found that where such jet action occurs in the filling of permanent molds the impact of the hot metal on the walls results both in serious wear and disintegration thereof and also in a

warping of the parts, especially the core 65 parts, on account of the localized over-heating of said parts.

It will be observed on reference to Fig. 3 that the inlet section 24 of the gate conduit partially overlies the liquid seal section 25 70 while the discharge section 26 of the gate conduit overlies the feeder 20. This compact form and arrangement of the gate parts makes it possible to reduce the bulk of the mold to a minimum for a casting cavity of 75 a given size.

I have shown my invention only in connection with molds for the production of piston castings but it is obviously applicable, in the production of castings of other articles and other forms and it will be understood that the foregoing disclosure is for purposes of illustration and explanation and not intended to define the scope of the invention. 80

85 What I claim is:

1. A mold having a cavity for the casting proper and provided with a gate comprising an upright feeder cavity adjacent the casting cavity and communicating with the casting cavity at various levels between the bottom and top thereof through a short narrow passage, said feeder cavity having its lateral wall opposite the casting cavity inclined downwardly and laterally toward 90 said casting cavity, and a supply passage extending from the gate inlet opening to the top of the feeder cavity, the discharge end of said supply passage being arranged to discharge the molten metal into the feeder 100 cavity only on lines substantially parallel to the inclined wall of said cavity. 95

2. A mold having a cavity for the casting proper and provided with a gate comprising an upright feeder cavity adjacent the casting cavity and communicating with the casting cavity at various levels between the bottom and top thereof through a short narrow passage, said feeder cavity having its lateral wall opposite the casting cavity inclined downwardly and laterally toward 105 said casting cavity, and a supply passage comprising a downwardly extending inlet section, a laterally and upwardly extending liquid seal section into which the inlet section 110 delivers and a discharge section arranged to receive molten metal from the liquid seal section and discharge it into the feeder cavity only on lines substantially parallel to the inclined wall of said cavity. 115

3. A mold having a cavity for the casting proper and provided with a gate comprising an upright feeder cavity adjacent the casting cavity and communicating with the casting cavity at various levels between the 125 bottom and top thereof through a short narrow passage, said feeder cavity having its lateral wall opposite the casting cavity

inclined downwardly and laterally toward said casting cavity, and a supply passage comprising a downwardly extending inlet section, a laterally extending section into 5 which the inlet section delivers, and a discharge section arranged to receive molten metal from the laterally extending section

and discharge it into the feeder cavity only on lines substantially parallel to the inclined wall of said cavity. 10

In testimony whereof, I hereunto affix my signature.

CLAIR J. AMICK.
